UNITED STATES PATENT OFFICE

136,298

DESIGN FOR A MINE ROCK DUSTING APPARATUS

Benjamin H. Van Vactor, Verona, Pa., assignor to
Mine Safety Appliances Company, Pittsburgh,
Pa.

Application August 20, 1941, Serial No. 102,961

Term of patent 14 years

To all whom it may concern:

Be it known that I, Benjamin H. Van Vactor, a citizen of the United States and a resident of Verona, in the county of Allegheny and State of Pennsylvania, have invented a new, original, and ornamental Design for a Mine Rock Dusting Apparatus, of which the following is a specification, reference being had to the accompanying drawings, forming a part thereof.

Fig. 1 is a top plan view of a mine rock dusting apparatus showing my new design, with the top cover plate removed;

Fig. 2 is a side elevational view thereof with the cover plate in place;

Fig. 3 is a front end elevational view thereof;

Fig. 4 is a side elevational view of the side opposite that in Fig. 2 with the cover plate removed; and

Fig. 5 is a top plan view thereof with the cover plate in its normal position.

I claim:

The ornamental design for a mine rock dusting apparatus, substantially as shown.

BENJAMIN H. VAN VACTOR.
